US00D987919S

(12) **United States Design Patent** (10) Patent No.: **US D987,919 S**
(45) Date of Patent: **** May 30, 2023**

(54) **BARK CONTROL DEVICE**

(71) Applicant: **Zhenggen Hu**, Hunan (CN)
(72) Inventor: **Zhenggen Hu**, Hunan (CN)
(**) Term: **15 Years**
(21) Appl. No.: **29/805,126**
(22) Filed: **Aug. 25, 2021**
(51) LOC (14) Cl. **30-99**
(52) U.S. Cl.

CLAIM

The ornamental design for a bark control device, as shown and described.

DESCRIPTION

FIG. 1 is a front, right and top perspective view of a bark control device, showing my design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof; and,

FIG. 7 is a bottom plan view thereof.

The broken lines shown in the drawings are included for the purpose of illustrating portions of the bark control device that form no part of the claimed design.

1 Claim, 7 Drawing Sheets
